United States Patent Office

Des. 215,938
Patented Nov. 11, 1969

215,938

CONTROL CONSOLE

Eliot F. Noyes, New Canaan, Conn., assignor to International Business Machines Corporation, Armonk, N.Y., a corporation of New York

Filed Dec. 16, 1968, Ser. No. 15,002

Term of patent 14 years

Int. Cl. D14—02

U.S. Cl. D26—5

FIG. 1

FIG. 2

FIG. 3

FIG. 4

FIG. 5

FIG. 6

FIGURE 1 is a front perspective view of a control console showing my new design;

FIGURE 2 is a rear perspective view thereof;

FIGURE 3 is a left side elevation thereof;

FIGURE 4 is a front elevation thereof;

FIGURE 5 is a right side elevation thereof;

FIGURE 6 is a top plan elevation thereof.

I claim:

The ornamental design for a control console, substantially as shown.
